DESIGN FOR A SCARF HAT OR SIMILAR ARTICLE

Lena Karlen, New York, N. Y.

Application April 3, 1943, Serial No. 109,902

Term of patent 3½ years

To all whom it may concern:

Be it known that I, Lena Karlen, a citizen of the United States of America, residing in New York City, county of New York, and State of New York, have invented a new, original, and ornamental Design for a Scarf Hat or Similar Article, of which the following is a specification, reference being had to the accompanying drawing, forming part thereof, wherein;

I claim:

The ornamental design for a scarf hat or similar article, substantially as shown.

LENA KARLEN.
